UNITED STATES PATENT OFFICE.

HUGO C. H. SCHROTH, OF SACRAMENTO, CALIFORNIA.

SUPPORTING-BRACKET.

1,171,667.

Specification of Letters Patent. Patented Feb. 15, 1916.

Application filed August 6, 1914. Serial No. 855,424.

To all whom it may concern:

Be it known that I, HUGO C. H. SCHROTH, a citizen of the United States, residing at Sacramento, county of Sacramento, State of California, have invented certain new and useful Improvements in Supporting-Brackets; and I do declare the following to be a clear, full, and exact description of the same, such as will enable others skilled in the art to which it appertains to make and use the same, reference being had to the accompanying drawings, and to the characters of reference marked thereon, which form a part of this application.

15 This invention relates to improvements in supporting brackets and is more particularly useful in adjusting insulators for electric wires as it may be readily and quickly adapted to meet various conditions as encountered 20 in outside line construction.

A further object of the invention is to produce a simple and inexpensive device and yet one which will be exceedingly effective for the purposes for which it is designed.

25 These objects, I accomplish by means of such structure and relative arrangement of the parts as will fully appear by a perusal of the following specification and claim.

On the drawings, similar characters of 30 reference indicate corresponding parts in the several views.

Figure 1 is a top plan view of the bracket as used to support an insulator placed on a corner. Fig. 2 is a side view of the bracket 35 used to support an insulator placed on a corner. Fig. 3 is a side view of the bracket as used to support an insulator against a flat surface. Fig. 4 is a side view of the bracket as used to support an insulator against a flat 40 surface, the brackets being changed to a different position. Fig. 5 is a top view of the bracket as used to fasten an insulator to one side of a corner. Fig. 6 is a side view of the bracket. Fig. 7 is an edge view of the 45 bracket.

Referring now more particularly to the characters of reference on the drawings, the numeral 1 designates a post or other means of support for the bracket 2 with holes 3 adapted to receive screws or bolts as may be 50 most suitable. The end 4 of the bracket is bent, as clearly shown in the drawing, and rounded off at the corners and provided with a hole 5 which carries in this case a bolt 6 with an insulator 7 disposed thereon. 55

To obtain the position shown in Fig. 3, the bracket on one side is removed from the bolt 6 and replaced in the position, as shown.

To obtain the position shown in Fig. 5, one bracket is swung around ninety degrees 60 to fit a corner, as shown.

From the foregoing description it will readily be seen that I have produced such a device as substantially fulfills the objects of the invention as set forth herein. 65

While this specification sets forth in detail the present and preferred construction of the device, still in practice, such deviations from such detail may be resorted to as do not form a departure from the spirit of 70 the invention, as defined by the appended claim.

Having thus described my invention what I claim as new and useful and desire to secure by Letters Patent is:— 75

A bracket, as described, comprising a flat body member, the same being bent at one end to form another portion lying in a plane disposed at right angles to said body member, the flat of said bent portion lying in a 80 plane outside of the plane of the adjacent edge of said body member, as described.

In testimony whereof I affix my signature in presence of two witnesses.

HUGO C. H. SCHROTH.
